(57) **CLAIM**

The ornamental design for a base unit for a vacuum assisted system for grooming hair as shown and described.

DESCRIPTION

FIG. 1 is a front-right-top perspective view of a base unit for a vacuum assisted system for grooming hair showing our new design;

FIG. 2 is a rear-right-top perspective view of the base unit for a vacuum assisted system for grooming hair of FIG. 1; FIG. 3 is a front view of the base unit for a vacuum assisted system for grooming hair of FIG. 1;

FIG. 4 is a rear view of the base unit for a vacuum assisted system for grooming hair of FIG. 1;

FIG. 5 is a left side view of the base unit for a vacuum assisted system for grooming hair of FIG. 1;

FIG. 6 is a right side view of the base unit for a vacuum assisted system for grooming hair of FIG. 1;

FIG. 7 is a top view of the base unit for a vacuum assisted system for grooming hair of FIG. 1; and,

FIG. 8 is a bottom view of the base unit for a vacuum assisted system for grooming hair of FIG. 1.

The broken lines shown in the drawings illustrate portions of the base unit for a vacuum assisted system for grooming hair that form no part of the claimed design.

1 Claim, 8 Drawing Sheets
